(57) **ABSTRACT**

A vibration suppression method and system of a rolling mill roller assembly based on a vibration damping device are provided. The vibration suppression method includes: obtaining a first amplitude-frequency relationship during a vibration process of a rolling mill roller assembly vibration suppression system; based on the first amplitude-frequency relationship, determining two time domain relationships and two second amplitude-frequency relationships by a simulation analysis; based on the two time domain relationships and two second amplitude-frequency relationships, adjusting parameters of the vibration damping device until a vibration displacement of the rolling mill roller assembly vibration suppression system is less than or equal to a vibration displacement threshold. And provides a new solution for the stability control of the rolling mill, and ensures the reliability and stability of the vibration suppression of the rolling mill.

VIBRATION SUPPRESSION METHOD AND SYSTEM OF A ROLLING MILL ROLLER ASSEMBLY BASED ON A VIBRATION DAMPING DEVICE

CROSS REFERENCE TO RELATED APPLICATIONS

This application claims foreign priority of Chinese Patent Application No. 202310840903.X, filed on Jul. 11, 2023 in the China National Intellectual Property Administration, the disclosures of all of which are hereby incorporated by reference.

TECHNICAL FIELD

This application relates to the technical field of vibration suppression of rolling mill, in particular to a vibration suppression method and system of a rolling mill roller assembly based on a vibration damping device.

BACKGROUND

Plate-strip rolling mill plays an important role in the field of heavy industry machinery. With the rapid development of science and technology, the requirements of strip mill in high-end field are getting higher and higher. However, the vibration of the rolling mill often occurs in the working process, which affects the quality and production efficiency of rolling products. It is difficult to meet the requirements of the rolling products in the high-end field. When the vibration is serious, it will damage the rolling equipment, causing economic losses, which limits the rapid development of the rolling industry.

At present, the action of mutually exclusive magnetic force is used to suppress the vibration of the rolling mill roller, or the damping force generated by the damping liquid flow is different through the different diameter of different solenoid valves, so as to realize the vibration reduction of the unit for different frequencies of the mill.

However, the method mentioned above for suppressing the vibration of the roll is passive vibration reduction method, which can only eliminate the high frequency vibration of the rolling mill roller, but can not eliminate the low frequency vibration and irregular vibration, and can not guarantee the reliability and stability of the vibration suppression of the rolling mill roller.

SUMMARY

This application provides a vibration suppression method and system of a rolling mill roller assembly based on a vibration damping device, to solve the technical problem that the existed passive vibration reduction method can only eliminate the high frequency vibration of the rolling mill roller, but can not eliminate the low frequency vibration and irregular vibration, and can not guarantee the reliability and stability of the vibration suppression of the rolling mill roller.

To realize the above objective, the present disclosure provides a vibration suppression method of a rolling mill roller assembly based on a vibration damping device, including:

S1: obtaining a first amplitude-frequency relationship during a vibration process of a rolling mill roller assembly vibration suppression system;

S2: based on the first amplitude-frequency relationship, determining two time domain relationships and two second amplitude-frequency relationships by a simulation analysis;

S3: based on the two time domain relationships and two second amplitude-frequency relationships, adjusting parameters of the vibration damping device until a vibration displacement of the rolling mill roller assembly vibration suppression system is less than or equal to a vibration displacement threshold.

The embodiments of the present application provides a vibration suppression method of a rolling mill roller assembly based on a vibration damping device, obtaining a first amplitude-frequency relationship during a vibration process of a rolling mill roller assembly vibration suppression system; based on the first amplitude-frequency relationship, determining two time domain relationships and two second amplitude-frequency relationships by a simulation analysis; based on the two time domain relationships and two second amplitude-frequency relationships, adjusting parameters of the vibration damping device until a vibration displacement of the rolling mill roller assembly vibration suppression system is less than or equal to a vibration displacement threshold. The present application obtains the first frequency amplitude relationship of the rolling gear vibration suppression system in the vibration amplitude process and adjusts the relevant parameter until the vibration displacement of the rolling gear is less than or equal to the preset vibration displacement threshold value. The present application obtains the interactive relationship between the vibration damping device and the rolling mill roll system through the time domain characteristics and amplitude frequency characteristics, appropriately adjusts the relevant parameters of the vibration reducing device to reduce the high frequency band, low frequency band and irregular vibration displacement of the rolling mill, provides a new solution for the stability control of the rolling mill, and ensures the reliability and stability of the vibration suppression of the rolling mill.

In another embodiment, S1 includes the following steps:

S11: establishing a simplified model corresponding to the rolling mill roller assembly vibration suppression system; wherein the vibration damping device is a kind of passive vibration damping device that connects a magnetorheological (MR) damper to an end of a rolling mill of a rolling mill roller assembly through sleeves and a bearing, and then connects a mass block to the MR damper through an elastic element and a damping element, after the vibration damping device is installed on the rolling mill roller assembly, a freedom system with two degrees is formed;

S12: calculating a corresponding relationship of the freedom system with two degrees of the rolling mill roller assembly vibration suppression system based on the simplified model;

S13: performing a data processing to the freedom system with two degrees by a multiscale method, to obtain the first amplitude-frequency relationship.

In another embodiment, S3 includes the following steps:

S31: determining a corresponding relationship between the parameters of the vibration damping device and the two second amplitude-frequency relationships by the simulation analysis;

S32: based on the two time domain relationships and the corresponding relationship between the parameters of the vibration damping device and the two second amplitude-frequency relationship, adjusting parameters of the vibration damping device until a vibration dis-

placement of the rolling mill roller assembly vibration suppression system is less than or equal to a vibration displacement threshold; wherein the parameters of the vibration damping device includes an initial damping force and damping force adjustable multiplying powers of the MR damper of the vibration damping device, a damping force and an inherent time delay of the passive damper of the damping device; **S31**: determining a corresponding relationship between the parameters of the vibration damping device and the two second amplitude-frequency relationships by the simulation analysis;

S32: based on the two time domain relationships and the corresponding relationship between the parameters of the vibration damping device and the two second amplitude-frequency relationship, adjusting parameters of the vibration damping device until a vibration displacement of the rolling mill roller assembly vibration suppression system is less than or equal to a vibration displacement threshold; wherein the parameters of the vibration damping device includes an initial damping force and damping force adjustable multiplying powers of the MR damper of the vibration damping device, a damping force and an inherent time delay of the passive damper of the damping device.

In another embodiment, the **S12** includes:

S12 includes following steps:

S121: obtaining an equivalent mass of a lower rolling mill roller assembly, an equivalent mass of the mass block of a passive damper corresponding to the vibration

stiffness, and k_1' is the equivalent nonlinear stiffness, and c_2 is the equivalent damping of the lower rolling mill roller assembly and the passive damper, and k_2 is the equivalent stiffness of the lower rolling mill roller assembly and the passive damper, $F \cos(\omega t)$ is a periodic external excitation that the rolling mill is subjected; $P \cdot D^p(x_{1\tau} - x_{2\tau})$ is an equivalent damping force of the MR damper of vibration the damping device between the lower rolling mill roller assembly and the passive damper; c_3 is an equivalent damping between the passive damper and a rolling mill stand of the lower rolling mill roller assembly, and k_3 is the equivalent stiffness of the passive damper and the rolling mill stand of the lower rolling mill roller assembly.

In another embodiment, **S13** includes the following steps:

S131: simplifying the corresponding relationship of the freedom system with two degrees to obtain a simplified corresponding relationship of the freedom system with two degrees;

S132: based on the initial damping force and the damping force adjustable multiplying powers, determining simplified equivalent damping force expressions of the MR damper;

S133: based on the simplified equivalent damping force expressions of the MR damper and corresponding relationship of a current freedom system with two degrees, performing the data processing to the freedom system with two degrees by a multiscale method, to obtain the first amplitude-frequency relationship.

In another embodiment, the corresponding relationship of the freedom system with two degrees includes:

$$\begin{cases} \ddot{x}_1 + \omega_{10}^2 x_1 = -\alpha_1 \dot{x}_1 - \beta_1(x_1 - \dot{x}_2) + \gamma_1 x_2 - \mu_1 x_1^3 - F_1 D^p(x_{1\tau} - x_{2\tau}) + F_0 \cos(\omega t); \\ \ddot{x}_2 + \omega_{20}^2 x_2 = \beta_2(x_1 - 2\dot{x}_2) + \gamma_2 x_1 + F_2 D^p(x_{1\tau} - x_{2\tau}) \end{cases};$$

wherein,

$$\omega_{10} = \sqrt{\frac{k_1 + k_2}{m_1}}, \omega_{20} = \sqrt{\frac{2k_2}{m_2}}, \alpha_1 = \frac{c_1}{m_1}, \beta_1 = \frac{c_2}{m_1}, \beta_2 = \frac{c_2}{m_2},$$

$$\gamma_1 = \frac{k_2}{m_1}, \gamma_2 = \frac{k_2}{m_2}, \mu_1 = \frac{k_1'}{m_1}, F_1 = \frac{P}{m_1}, F_2 = \frac{P}{m_2}, F_0 = \frac{F}{m_1};$$

the simplified equivalent damping force expressions of the MR damper includes:

$$\begin{cases} F_1 \cdot D^p(x_{2\tau}) = \eta_1 \rho_1 D^p(x_{1\tau} - x_{2\tau}); \\ F_2 \cdot D^p(x_{2\tau}) = \eta_2 \rho_2 D^p(x_{1\tau} - x_{2\tau}) \end{cases};$$

damping device, and an equivalent damping between the lower rolling mill roller assembly and a rolling piece, and an equivalent linear stiffness, and an equivalent nonlinear stiffness, and an equivalent damping and an equivalent stiffness of the lower rolling mill roller assembly and the passive damper;

S122: calculating a corresponding relationship of the freedom system with two degrees of the rolling mill roller assembly vibration suppression system based on the equivalent mass of a lower rolling mill roller assembly, the equivalent mass of the mass block of the passive damper, and the equivalent damping between the lower rolling mill roller assembly and the rolling piece, and the equivalent linear stiffness, and the equivalent nonlinear stiffness, and the equivalent damping and the equivalent stiffness of the lower rolling mill roller assembly and the passive damper.

In another embodiment, the the corresponding relationship of the freedom system with two degrees includes:

$$\begin{cases} m_1 \ddot{x}_1 + c_1 \dot{x}_1 + c_2(x_1 - \dot{x}_2) + k_1 x_1 + k_1' x_1^3 + k_2(x_1 - x_2) + P \cdot D^p(x_{1\tau} - x_{2\tau}) - F \cos(\omega t) = 0; \\ m_2 \ddot{x}_2 - c_2(x_1 - \dot{x}_2) + c_3 x_2 - k_2(x_1 - x_2) + k_3 x_2 - P \cdot D^p(x_{1\tau} - x_{2\tau}) = 0 \end{cases};$$

wherein, m_1 is the equivalent mass of a lower rolling mill roller assembly, m_2 is the equivalent mass of the mass block of the passive damper, and c_1 is the equivalent damping between the lower rolling mill roller assembly and the rolling piece, and k_1 is the equivalent linear

stiffness, and η_1 and η_2 are initial damping force coefficients of the MR damper, ρ_1 and ρ_2 are damping force adjustable multiplying powers of the MR damper; the two second amplitude-frequency relationship includes:

$$\left(\frac{\eta_1 \rho_1 \omega_{10}^p a \cos\left(\frac{p\pi}{2}\right) e^{-i\omega_{10}\tau}}{2} - \omega_{10} a \sigma + \frac{3\mu_1 a^3}{8} \right)^2 + \left(\frac{\eta_1 \rho_1 \omega_{10}^p a \sin\left(\frac{p\pi}{2}\right) e^{-i\omega_{10}\tau}}{2} + \frac{\alpha_1 \omega_{10} a}{2} + \frac{\beta_1 \omega_{10} a}{2} \right)^2 = \frac{F_0^2}{4};$$

the present application also provides a vibration suppression system of a rolling mill roller assembly based on a vibration damping device, the vibration suppression system includes:

a controlling equipment, a vibration damping device being connected to the controlling equipment, and a rolling mill roller assembly being connected to the vibration damping device;

the controlling equipment is configured to obtain first amplitude-frequency relationship during a vibration process of a rolling mill roller assembly vibration suppression system;

the controlling equipment is also configured to determine two time domain relationships and two second amplitude-frequency relationships by a simulation analysis, based on the first amplitude-frequency relationship;

the controlling equipment is also configured to adjust parameters of the vibration damping device until a vibration displacement of the rolling mill roller assembly vibration suppression system is less than or equal to a vibration displacement threshold, based on the two time domain relationships and two second amplitude-frequency relationships;

wherein the vibration damping device includes a mounting bearing, a MR damper, a passive damper, a supporting rod and a magnetic sucker;

wherein the rolling mill roller assembly includes a rolling mill stand and a rolling mill roller, wherein the rolling mill stand is connected with the magnetic sucker, the rolling mill roller is connected with the supporting rod; wherein the controlling equipment is connected with the MR damper and the rolling mill roller;

wherein the controlling equipment includes a plurality of acceleration sensors, a first calculation member, and a second calculation member, and a controller; wherein two of the acceleration sensors are connected with each other, and the controller is connected with the MR damper;

wherein the MR damper is configured to determine the vibration displacement of the rolling mill roller through the acceleration sensors;

wherein the MR damper and the passive damper is configured to absorb part of the vibration energy of the rolling mill roller.

The beneficial effect of the rolling mill roller assembly vibration suppression system based on the vibration reduction device provided by the second aspect is the same as the beneficial effect of the vibration suppression method of the rolling roller based on the vibration reduction device described in any possible implementation of the first aspect or the first aspect, which will not be repeated here.

BRIEF DESCRIPTION OF THE DRAWINGS

The drawings illustrated are provided a further understanding of this application and form part of the present application, and the schematic embodiments of the present

application and their instructions used to interpret the application and are not intended to limitation this application. In the attached drawings:

LABELS AND DESCRIPTION

101—a controlling equipment; **102**—a vibration damping device; **103**—a rolling mill roller assembly; **1031**—a rolling mill stand; **1032**—a mill roll; **1021**—a mounting bearing; **1022**—a MR damper; **1023**—a passive damper; **1024**—a supporting rod; **1025**—a magnetic sucker; **1021a**—a thrust bearing; **1021b**—a connecting end of the mounting bearing; **1022a**—an upper connecting end; **1022b**—a lower connecting end; **1022c**—a first guiding rod; **1022d**—a first end cover; **1022e**—a first sleeve; **1022f**—a wire barrel; **1022g**—an envelope; **1022h**—a first bolt; **1022i**—a first nut; **1022j**—a rubber sealing ring; **1023a**—a second end cover; **1023b**—a second sleeve; **1023c**—a connecting end; **1023d**—a second guiding end; **1023f**—a mass block; **1023g**—a second bolt; **1023h**—a second nut; **1023i**—a screw; **1011**—an acceleration sensor; **1012**—a first calculation member; **1013**—a second calculation member; **1014**—a controller; **1032a**—a mill roll upper roller; **1032b**—a mill roll lower roller; **1032c**—a protrusion of the mill roll lower roller.

DETAILED DESCRIPTION OF THE EMBODIMENTS

In order to facilitate a clear description of the technical solutions of the embodiment of the present application, in the embodiment of the present application, the words “first” and “second” are used to distinguish the same or similar items with basically the same functions and functions. For example, the first and second thresholds are only designed to distinguish between different thresholds and do not define their order. Those skilled in the art can understand that the words “first” and “second” do not limit the number and order of execution, and that the words “first” and “second” are not necessarily different.

It should be noted that in the present application, the words “exemplary” or “for example” are used to represent examples, illustrations or explanations. Any embodiment or design scheme described in this application as “exemplary” or “for example” should not be construed as more preferred or superior over other embodiments or designs. Specifically, the words “exemplary” or “for example” are used to present relevant concepts in a specific way.

In this application, “at least one” means one or more, and “more” means two or more. “And/or”, describing the association relationship of the associated object, indicates that there can be three relationships, for example, A and/or B, which can indicate: A alone, A and B together, and B alone, where A and B can be singular or plural. The character “/” generally indicates that the associated object is a relationship of “or”. At least one of the following item(s) or its similar expression means any combination of these items, including any combination of individual item(s) or plural item(s). For example, at least one term in a, b or c can indicate the combination of a, b, c, a and b, combination of a and c, combination of b and c, or combination of a, b and c, where a, b, c can be single or multiple.

MR damper is a semi-active execution device based on MR effect. It has the advantages of low energy consumption, fast response speed, simple structure and continuously adjustable damping force. MR damper is an ideal device for semi-automatic control and is widely used in various vibration and shock control systems. At the same time, passive dampers such as mass block, particle damping or magnetic effect are widely used in vibration damping system of rolling mill roller, and the active and passive combined vibration reduction method has been fully utilized in automobile, aircraft rotor, robot and other fields. However, has not been applied in rolling mill roller vibration suppression, therefore, the embodiment of this application provides a vibration suppression method of the rolling mill roller assembly based on vibration reduction device thereof, to solve problems of passive vibration reduction method, which can only eliminate the high frequency vibration of the rolling roll roller, but can not eliminate the low frequency vibration and irregular vibration, and can not guarantee the reliability and stability of the vibration suppression of the rolling roll roller.

FIG. 1 is a schematic diagram of a vibration suppression system of a rolling mill roller assembly based on a vibration damping device of an embodiment of the present application, as shown in FIG. 1, the vibration suppression system of a rolling mill roller assembly includes:

a controlling equipment **101**, a vibration damping device **102** is connected to the controlling equipment, and a rolling mill roller assembly **103** is connected to the vibration damping device **102**.
The controlling equipment **101** is used to the controlling equipment is configured to obtain first amplitude-frequency relationship during a vibration process of a rolling mill roller assembly vibration suppression system; and the controlling equipment is also configured to determine two time domain relationships and two second amplitude-frequency relationships by a simulation analysis, based on the first amplitude-frequency relationship; and the controlling equipment is also configured to adjust parameters of the vibration damping device until a vibration displacement of the rolling mill roller assembly vibration suppression system is less than or equal to a vibration displacement threshold, based on the two time domain relationships and two second amplitude-frequency relationships.

As shown in FIG. 1, the rolling mill roller assembly **103** includes a rolling mill stand **1031** and a rolling mill roller **1032**; the rolling mill stand **1031** is connected to the magnetic sucker **1025**; the rolling mill roller **1032** and the mounting bearing **1021**; and the controlling equipment **101** is connected with the MR damper **1022** and the rolling mill roller **1032**.

Specifically, referring to FIG. 1, the rolling mill roller **1032** includes a rolling mill upper roller **1032a**, a rolling mill lower roller **1032b**, and a protrusion of the rolling mill roller **1032c**.

FIG. 2 is a schematic diagram of a vibration damping device of an embodiment of the present application, as shown in FIG. 2, The vibration damping device **102** includes a mounting bearing **1021**, a MR damper **1022**, and a passive damper **1023**, and a supporting rod **1024**, and a magnetic sucker **1025**. An end of the mounting bearing **1021** is provided with an external thread, and the mounting bearing **1021** connects with an upper of the MR damper **1022** by an internal thread fitting connection. A lower end of the MR damper **1022** is provided with an external thread, and is connected with the passive damper **1023** by an external thread fitting connection. An upper cover of the passive damper **1023** is provided with internal thread, and is con-

nected with the supporting rod 1024 by an external thread fitting connection, and another end of the supporting rod 1024 is connected with the magnetic sucker 1025 by internal thread fitting connection.

FIG. 3 is a schematic diagram of a MR damper and a mounting bearing of an embodiment of the present application. As shown in FIG. 3, the mounting bearing 1021 includes a thrust bearing 1021a and a connecting end of the mounting bearing 1021b. The MR damper 1022 includes an upper connecting end 1022a, lower connecting end 1022b, and a first guiding end 1022c, and a first end cover 1022d, and a first sleeve 1022e, and a wire barrel 1022f, and an envelope 1022g, and a first bolt 1022h, and a first nut 1022i, and a rubber sealing ring 1022j.

Please refers to FIG. 3, the upper connecting end 1022a is firmly connected to the first guiding end 1022c, the first guiding end 1022c passes through a link hole of the first end cover 1022d, and the first guiding end 1022c is connected to the barrel 1022f. A protruding portion is provided on a rod of the first guiding end 1022c, and is fix by a nut. The first guiding end 1022c and link hole of the first end cover 1022d are sealed through a rubber sealing ring, to prevent magnetorheological fluid leakage. A wire hole is defined inside the first guiding end 1022c, an envelope 1022g connects the controlling equipment through the wire hole. In the MR damper, the envelope 1022g is wrapped around the barrel 1022f. The first sleeve 1022e is connected to the first end cover 1022d by a bolt and a nut. The first end cap 1022d and the first sleeve 1022e are sealed by the rubber sealing ring, to prevent magnetorheological fluid leakage. The first sleeve 1022e is firmly connected with the lower connecting end 1022b.

FIG. 4 is a schematic diagram of a MR damper and a mounting bearing of another embodiment of the present application, FIG. 5 is a schematic diagram of another view of the MR damper and the mounting bearing of FIG. 4 as shown in FIG. 4 and FIG. 5, the mounting bearing 1021 and the MR damper 1022 are connected.

FIG. 6 is a schematic diagram of a passive damper of an embodiment of the present application; FIG. 6 is a schematic diagram of an second end cover and second sleeve of the passive damper of an embodiment of the present application; as shown in FIG. 5A, the passive damper includes a second end cover 1023a, and a second sleeve 1023b, and a connecting end 1023c, and a second guiding end 1023d, and a spring (not marked in the figure), and a mass block 1023f, and a second bolt 1023g, and a second nut 1023h, and a screw 1023i. An outer center of the second end cover 1023a has an inner thread hole. The second end cover 1023a has a penetrating screw hole and a second bolt hole. The second sleeve 1023b is connected to the second end cover 1023a by the second bolt 1023g of the second nut 1023h. The second sleeve 1023b also has a penetrating screw hole. The second guide 1023d rod has a non-penetration thread, the second guiding end 1023d is connected to a bottom of the second sleeve 1023b and the second end cover 1023a through the screw 1023i. The mass block 1023f is defined with a penetration hole, the mass block 1023f is inside the passive damper 1023 through the second guiding end 1023d. Two ends of the mass block 1023f through springs to connect the inner bottom of the second sleeve 1023b and a bottom of the second end cover 1023a along the second guiding end 1023d. The second sleeve 1023b is firmly connected to the connecting end 1023c. When the roller vibrate vertically, the roller vibration energy is transferred to the passive damper, the passive damper absorbs part of the vibration energy and change into a kinetic energy of the mass block 1023f and a

potential energy of the spring, thus reducing the vibration displacement of the roller. As shown in FIG. 7, the passive damper includes a second end cover 1023a and a second sleeve 1023b.

FIG. 8 is another schematic diagram a vibration suppression system of a rolling mill roller assembly based on a vibration damping device of an embodiment of the present application. As shown in FIG. 8, the controlling equipment 101 includes a plurality of acceleration sensors 1011, a first calculation member 1012, and a second calculation member 1013, and a controller 1014. Two of the acceleration sensors 1012 are connected with each other, and the controller 1014 is connected with the MR damper 1022. The MR damper 1022 is configured to determine the vibration displacement of the rolling mill roller 1032 through the acceleration sensors 1011. The MR damper 1022 and the passive damper are used to absorb part of the vibration energy of the rolling mill roller 1032.

As shown in FIG. 1 or FIG. 8, the MR damper is connected with controller equipment, measuring the displacement of the outer frame end of the rolling mill through a three-way displacement sensor instead of the roller end displacement. When the displacement exceeds a certain threshold, the controller equipment applies a current to the MR damper. When the vertical vibration of the rolling mill roller exceeds a certain threshold, the vibration energy of the rolling mill roller is transferred to the MR damper, and the magnetorheological fluid of the MR damper may occur electromagnetic reaction, and the viscosity increases and absorbs the vibration displacement of the roller.

FIG. 9 is a schematic diagram of a vibration suppression method of a rolling mill roller assembly based on a vibration damping device of an embodiment of the present application. The schematic diagram of a vibration suppression method is applied to the vibration suppression system of the rolling mill roller assembly based on the vibration damping device, a controlling equipment and a rolling mill roller assembly shown in FIGS. 1-8, as shown in FIG. 9, the vibration suppression method includes:

S1: obtaining a first amplitude-frequency relationship during a vibration process of a rolling mill roller assembly vibration suppression system;

S2: based on the first amplitude-frequency relationship, determining two time domain relationships and two second amplitude-frequency relationships by a simulation analysis, wherein the two time domain relationships are corresponding to a working state and a non working state of the rolling mill roller assembly vibration suppression system, and the two second amplitude-frequency relationships are corresponding to the working state and the non working state of the rolling mill roller assembly vibration suppression system;

S3: based on the two time domain relationships and two second amplitude-frequency relationships, adjusting parameters of the vibration damping device until a vibration displacement of the rolling mill roller assembly vibration suppression system is less than or equal to a vibration displacement threshold.

In summary, the present embodiment provides a vibration suppression method of a rolling mill roller assembly based on a vibration damping device, obtaining a first amplitude-frequency relationship during a vibration process of a rolling mill roller assembly vibration suppression system; based on the first amplitude-frequency relationship, determining two time domain relationships and two second amplitude-frequency relationships by a simulation analysis, wherein the two time domain relationships are corresponding to a work-

11

ing state and a non working state of the rolling mill roller assembly vibration suppression system, and the two second amplitude-frequency relationships are corresponding to the working state and the non working state of the rolling mill roller assembly vibration suppression system; based on the two time domain relationships and two second amplitude-frequency relationships, adjusting parameters of the vibration damping device until a vibration displacement of the rolling mill roller assembly vibration suppression system is less than or equal to a vibration displacement threshold. The present application obtains the interactive relationship between the vibration damping device and the rolling mill roll system through the time domain characteristics and amplitude-frequency characteristics, appropriately adjusts the relevant parameters of the vibration reducing device to reduce the high frequency band, low frequency band and irregular vibration displacement of the rolling mill roller assembly, provides a new solution for the stability control of the rolling mill roller assembly, and ensures the reliability and stability of the vibration suppression of the rolling mill roller assembly.

FIG. 10 is a schematic diagram of a vibration suppression method of a rolling mill roller assembly based on a vibration damping device of another embodiment of the present application, applied to a vibration suppression system including a vibration damping device, a controlling equipment, and a rolling mill roller assembly vibration suppression system shown in FIGS. 1-8, as shown in FIG. 10, S1 includes:

$$\begin{cases} m_1\ddot{x}_1 + c_1\dot{x}_1 + c_2(\dot{x}_1 - \dot{x}_2) + k_1x_1 + k'_1x_1^3 + k_2(x_1 - x_2) + P \cdot D^p(x_{1\tau} - x_{2\tau}) - F \cos(\omega t) = 0; \\ m_2\ddot{x}_2 - c_2(\dot{x}_1 - \dot{x}_2) + c_3x_2 - k_2(x_1 - x_2) + k_3x_2 - P \cdot D^p(x_{1\tau} - x_{2\tau}) = 0 \end{cases}$$

S11: establishing a simplified model corresponding to the rolling mill roller assembly vibration suppression system;

In this application, the vibration damping device is a kind of passive vibration damping device that connects a MR damper to an end of a rolling mill of a rolling mill roller assembly through sleeves and a bearing, and then connects a mass block to the MR damper through an elastic element and a damping element, after the vibration damping device is installed on the rolling mill roller assembly, a freedom system with two degrees is formed. In ideal conditions, the rolling mill roller and the vibration damping device only make a straight movement in the vertical direction of the rolling mill roller. When the system is static and the equilibrium position of the damping device is the moving origin, and a value of the vibration displacement of the rolling mill roller and the vibration represents strength. When needs to reduce the vibration of the rolling mill roll train, it needs to reduce the vibration displacement. The rolling mill roller assembly vibrates under the external excitation, and a vibration energy of the rolling mill roll system is transferred to the main and passive combined damper through the electromagnetic reaction of the MR damper. A force of the vibration damping on the rolling mill roller assembly through the MR damper, elastic element and damping element is opposite to the external force on the rolling mill assembly. Thus, the vibration energy of the mill roll system is transferred to the magnetic rheological fluid and the kinetic energy of the passive vibration damping device, to reduce the vibration displacement of the rolling mill roller assembly, and to achieve the effect of inhibiting the vibration.

12

S12: calculating a corresponding relationship of the freedom system with two degrees of the rolling mill roller assembly vibration suppression system based on the simplified model;

S13: process the data of the corresponding relationship of the two degrees of freedom systems and determine the first frequency amplitude relationship.

As shown in FIG. 11, S12 includes:

S121: obtaining an equivalent mass of a lower rolling mill roller assembly, an equivalent mass of the mass block of a passive damper corresponding to the vibration damping device, and an equivalent damping between the lower rolling mill roller assembly and a rolling piece, and an equivalent linear stiffness, and an equivalent nonlinear stiffness, and an equivalent damping and an equivalent stiffness of the lower rolling mill roller assembly and the passive damper;

S122: calculating a corresponding relationship of the freedom system with two degrees of the rolling mill roller assembly vibration suppression system based on the equivalent mass of a lower rolling mill roller assembly, the equivalent mass of the mass block of the passive damper, and the equivalent damping between the lower rolling mill roller assembly and the rolling piece, and the equivalent linear stiffness, and the equivalent nonlinear stiffness, and the equivalent damping and the equivalent stiffness of the lower rolling mill roller assembly and the passive damper.

Wherein the corresponding relationship of the freedom system with two degrees includes:

35

Among them, m_1 is the equivalent mass of a lower rolling mill roller assembly, m_2 is the equivalent mass of the mass block of the passive damper, and c_1 is the equivalent damping between the lower rolling mill roller assembly and the rolling piece, and k_1 is the equivalent linear stiffness, and k'_1 is the equivalent nonlinear stiffness, and c_2 is the equivalent damping of the lower rolling mill roller assembly and the passive damper, and k_2 is the equivalent stiffness of the lower rolling mill roller assembly and the passive damper, $F \cos(\omega t)$ is a periodic external excitation that the rolling mill is subjected; $P \cdot D^p(x_{1\tau} - x_{2\tau})$ is an equivalent damping force of the MR damper of vibration the damping device between the lower rolling mill roller assembly and the passive damper; c_3 is an equivalent damping between the passive damper and a rolling mill stand of the lower rolling mill roller assembly, and k_3 is the equivalent stiffness of the passive damper and the rolling mill stand of the lower rolling mill roller assembly.

FIG. 12 is a schematic diagram of a simplified model of a vibration suppression method of a rolling mill roller assembly based on a vibration damping device of an embodiment of the present application, as shown in FIG. 12, The For the equivalent mass of the roll line under the rolling mill, For the equivalent mass of the described passive damper mass block, The equivalent damping between the lower roll train and the piece is The equivalent linear stiffness and the equivalent nonlinear stiffness are and, respectively, The equivalent damping between the lower roller train and the passive damper is, The stated equivalent stiffness is defined as, It is approximate that the roll is subject to a periodic external excitation of; For the equiva-

lent damping force of the magnetic rheological damper in the vibration damper between the lower roller train and the passive damper, The equivalent damping between the passive shock absorber and the rolling mill stand is, The equivalent stiffness is, Since the MR dampers belong to the class of active dampers, Mainly through the electromagnetic reaction to achieve the vibration reduction effect, Thus the equivalent quality of the MR damper itself has no effect on the damping effect, Thus, the equivalent mass block of the MR damper should not be reflected in the 2 D model diagram.

As shown in FIG. 13, S13 includes:

S131: simplifying the corresponding relationship of the freedom system with two degrees to obtain a simplified corresponding relationship of the freedom system with two degrees;

S132: based on the initial damping force and the damping force adjustable multiplying powers, determining simplified equivalent damping force expressions of the MR damper;

S133: based on the simplified equivalent damping force expressions of the MR damper and corresponding relationship of a current freedom system with two degrees, performing the data processing to the freedom system with two degrees by a multiscale method, to obtain the first amplitude-frequency relationship.

Wherein, the corresponding relationship of the simplified freedom system with two degrees:

$$\begin{cases} \ddot{x}_1 + \omega_{10}^2 x_1 = -\alpha_1 \dot{x}_1 - \beta_1 (x_1 - \dot{x}_2) + \gamma_1 x_2 - \mu_1 x_1^3 - F_1 D^p(x_{1\tau} - x_{2\tau}) + F_0 \cos(\omega t) \\ \ddot{x}_2 + \omega_{20}^2 x_2 = \beta_2 (x_1 - 2\dot{x}_2) + \gamma_2 x_1 + F_2 D^p(x_{1\tau} - x_{2\tau}) \end{cases};$$

wherein,

$$\begin{aligned} \omega_{10} &= \sqrt{\frac{k_1 + k_2}{m_1}}, \omega_{20} = \sqrt{\frac{2k_2}{m_2}}, \alpha_1 = \frac{c_1}{m_1}, \beta_1 = \frac{c_2}{m_1}, \beta_2 = \frac{c_2}{m_2}, \\ \gamma_1 &= \frac{k_2}{m_1}, \gamma_2 = \frac{k_2}{m_2}, \mu_1 = \frac{k'_1}{m_1}, F_1 = \frac{P}{m_1}, F_2 = \frac{P}{m_2}, F_0 = \frac{F}{m_1}; \end{aligned}$$

the simplified equivalent damping force expressions of the MR damper includes:

$$\begin{cases} F_1 \cdot D^p(x_{2\tau}) = \eta_1 \rho_1 D^p(x_{1\tau} - x_{2\tau}) \\ F_2 \cdot D^p(x_{2\tau}) = \eta_2 \rho_2 D^p(x_{1\tau} - x_{2\tau}) \end{cases};$$

wherein, η_1 and η_2 are initial damping force coefficients of the MR damper, ρ_1 and ρ_2 are damping force adjustable multiplying powers of the MR damper; the two second amplitude-frequency relationship comprises:

$$\begin{aligned} &\left(\frac{\eta_1 \rho_1 \omega_{10}^p \cos\left(\frac{p\pi}{2}\right) e^{-i\omega_{10}\tau}}{2} - \omega_{10} a \sigma + \frac{3\mu_1 a^3}{8} \right)^2 + \\ &\left(\frac{\eta_1 \rho_1 \omega_{10}^p \sin\left(\frac{p\pi}{2}\right) e^{-i\omega_{10}\tau}}{2} + \frac{\alpha_1 \omega_{10} a}{2} + \frac{\beta_1 \omega_{10} a}{2} \right)^2 = \frac{F_0^2}{4} \end{aligned}$$

In this application, the corresponding time domain curve and amplitude frequency curve of the vibration damping system in the operating state can be obtained by simulation.

FIG. 14 is a diagram of two time domain curves corresponding to a working state and a non working state of the rolling mill roller assembly vibration suppression system of an embodiment of the present application. As shown in FIG. 14, it can be seen that the stability amplitude of the vibration displacement of the rolling roller gear is 8.610 before the vibration damping device is in the non-working state-5, the m (curve 401) decreases to 6.510 when the vibration damping device is added with the vibration damping device-5 And 10 m (curve 402). It can be determined that the vibration reducing device reduces the vibration amplitude of the rolling roll system.

As shown in FIG. 15, S3 includes:

S31: determining a corresponding relationship between the parameters of the vibration damping device and the two second amplitude-frequency relationships by the simulation analysis.

S32: based on the two time domain relationships and the corresponding relationship between the parameters of the vibration damping device and the two second amplitude-frequency relationship, adjusting parameters of the vibration damping device until a vibration displacement of the rolling mill roller assembly vibration suppression system is less than or equal to a vibration displacement threshold.

Wherein the parameters of the vibration damping device includes an initial damping force and damping force adjustable multiplying powers of the MR damper of the vibration

35 damping device, a damping force and an inherent time delay of the passive damper of the damping device.

FIG. 16 is a diagram of an amplitude-frequency curve corresponding to a non working state of the rolling mill roller assembly vibration suppression system of an embodiment of the present application, FIG. 17 is a schematic diagram of the corresponding relationship between the initial damping force and a amplitude-frequency characteristics of the rolling mill roller assembly vibration suppression system of an embodiment of the present application, FIG. 18 is a schematic diagram of the corresponding relationship between the damping force adjustable multiplying powers and the vibration amplitude-frequency characteristics of the rolling mill roller assembly of an embodiment of the present application, FIG. 19 is a schematic diagram of a corresponding relationship between the damping force of a pair of passive dampers and a vibration amplitude-frequency characteristics of the rolling mill roller assembly of an embodiment of the present application, FIG. 20 is a schematic diagram of the corresponding relationship of an inherent time delay of a pair of passive dampers and a vibration amplitude frequency characteristics of the rolling mill roller assembly of an embodiment of the present application, The horizontal axis of Figure FIG. 16-Figure FIG. 20 shows the frequency, The vertical axis represents the magnitude amplitude.

Comparing FIGS. 16 to 20, it is clearly that the height of the amplitude and frequency curve and the bending curve of the mill roller system is reduced, that is, the vibration reducing device affects the effectiveness of the system stability to illustrate the vibration control of the mill roller system.

15

Refers to FIGS. 17 to 18, the change of the damping force of the MR damper and the passive damper changes the height of the amplitude frequency characteristic curve, i. e. the passive damping force affects the vibration amplitude of the system; in the active control, the inherent time delay cannot be ignored, which shows from FIG. 20 that the change changes the height of the amplitude frequency characteristic curve, that is, the inherent time delay affects the vibration amplitude of the system and increases the vibration amplitude value.

That is, it is possible to determine the corresponding relationship between the relevant parameters of the vibration damping device and the second frequency-amplitude relationship, including: the height of the amplitude frequency curve of the rolling roller and the change of the inherent time delay changes the height of the amplitude frequency characteristic curve, that is, the inherent time delay affects the vibration amplitude of the system and increases the vibration amplitude value.

In this application, the preset vibration displacement threshold can be adjusted according to the actual application scenario, obtaining the mutual relationship between the vibration damping device and the corresponding relationship between the corresponding parameters and the second frequency amplitude relationship, adjusting the initial damping of the adjustable multiplier, and reducing the vibration displacement of the rolling mill system, thus improving the stability of the rolling mill system, thus providing a new solution for the stability control of the rolling mill system.

In summary, the vibration suppression method provided by the embodiment of the present application obtains the first frequency amplitude relationship of the rolling gear vibration suppression system in the vibration amplitude process and adjusts the relevant parameter until the vibration displacement of the rolling gear is less than or equal to the preset vibration displacement threshold value. The present application obtains the interactive relationship between the vibration damping device and the rolling mill roll system through the time domain characteristics and amplitude frequency characteristics, appropriately adjusts the relevant parameters of the vibration reducing device to reduce the high frequency band, low frequency band and irregular vibration displacement of the rolling mill, provides a new solution for the stability control of the rolling mill, and ensures the reliability and stability of the vibration suppression of the rolling mill.

A rolling roller vibration suppression method based on vibration damping device provided in this application can be implemented in the vibration suppression system as shown in FIGS. 1-8, and will not be repeated in order to avoid repetition.

As shown in FIG. 21, the controlling equipment also includes: a processor 1001 (such as Central Processing Unit, CPU), a communication bus 1002, an input port 1003, an output port 1004, and a memory 1005. Among them, the communication bus 1002 is used to achieve connection communication between these components; the input port 1003 is used for data input; and the output port 1004 is used for data output, and the memory 1005 can be high-speed RAM memory or non-volatile memory, such as disk memory, non-transitory computer-readable storage medium. Optionally, memory 1005 is a storage device independent of the aforementioned processor 1001.

The memory 1005, as a non-volatile readable storage medium, may include an operating system, network communication module, application program module, and a vibration suppression program of the rolling mill roller

16

assembly based on the vibration damping device. The network communication module is mainly used to connect to servers and communicate data with them; And processor 1001 is used to call the program to process the method stored in memory 1005, and execute all steps of vibration suppression method of the rolling mill roller assembly based on the vibration damping device mentioned above.

Although the present application is described in combination with specific features and its embodiments, various modifications and combinations may be made without departing from the spirit and scope of the present application. Accordingly, the specification and drawings are merely an exemplary illustration of the application as defined in the attached claims and are deemed to have covered any and all modifications, changes, combinations or equivalent within the scope of the application. Clearly, persons skilled in the art may make various changes and modifications to this application without departing from the spirit and scope of the present application. Thus, if these modifications and variations of the present application are within the scope of the present claims and their equivalent technology, the present application is also intended to include these modifications and variants.

The invention claimed is:

1. A vibration suppression method of a rolling mill roller assembly based on a vibration damping device, wherein, comprising following steps:

S1: obtaining a first amplitude-frequency relationship during a vibration process of a rolling mill roller assembly vibration suppression system;

S2: based on the first amplitude-frequency relationship, determining two time domain relationships and two second amplitude-frequency relationships by a simulation analysis, wherein the two time domain relationships are corresponding to a working state and a non working state of the rolling mill roller assembly vibration suppression system, and the two second amplitude-frequency relationships are corresponding to the working state and the non working state of the rolling mill roller assembly vibration suppression system;

S3: based on the two time domain relationships and two second amplitude-frequency relationships, adjusting parameters of the vibration damping device until a vibration displacement of the rolling mill roller assembly vibration suppression system is less than or equal to a vibration displacement threshold;

wherein, S1 comprises following steps:

S11: establishing a simplified model corresponding to the rolling mill roller assembly vibration suppression system; wherein the vibration damping device is a kind of passive vibration damping device that connects a magnetorheological (MR) damper to an end of the rolling mill of the rolling mill roller assembly through sleeves and a bearing, and then connects a mass block to the IR damper through an elastic element and a damping element, after the vibration damping device is installed on the rolling mill roller assembly, a freedom system with two degrees is formed;

S12: calculating a corresponding relationship of the freedom system with two degrees of the rolling mill roller assembly vibration suppression system based on the simplified model;

S13: performing a data processing to the freedom system with two degrees by a multiscale method, to obtain the first amplitude-frequency relationship;

wherein, S12 comprises following steps:

S121: obtaining an equivalent mass of the lower rolling mill roller assembly, an equivalent mass of the mass block of a passive damper corresponding to the vibration damping device, and an equivalent damping between the lower rolling mill roller assembly and a rolling piece, and an equivalent linear stiffness, and an equivalent nonlinear stiffness, and an equivalent damping and an equivalent stiffness of the lower rolling mill roller assembly and the passive damper;

S122: calculating a corresponding relationship of the freedom system with two degrees of the rolling mill roller assembly vibration suppression system based on the equivalent mass of a lower rolling mill roller assembly, the equivalent mass of the mass block of the passive damper, and the equivalent damping between the lower rolling mill roller assembly and the rolling piece, and the equivalent linear stiffness, and the equivalent nonlinear stiffness, and the equivalent damping and the equivalent stiffness of the lower rolling mill roller assembly and the passive damper;

wherein, S3 comprises following steps:

S31: determining a corresponding relationship between the parameters of the vibration damping device and the two second amplitude-frequency relationships by the simulation analysis;

S32: based on the two time domain relationships and the corresponding relationship between the parameters of the vibration damping device and the two second amplitude-frequency relationship, adjusting the parameters of the vibration damping device until the vibration displacement of the rolling mill roller assembly vibra-

wherein

$$\left\{ \begin{array}{l} \ddot{x}_1 + \omega_{10}^2 x_1 = -\alpha_1 \dot{x}_1 - \beta_1 (\dot{x}_1 - \dot{x}_2) + \gamma_1 x_2 - \mu_1 x_1^3 - F_1 D^p(x_{1\tau} - x_{2\tau}) + F_0 \cos(\omega t); \\ \ddot{x}_2 + \omega_{20}^2 x_2 = \beta_2 (\dot{x}_1 - 2\dot{x}_2) + \gamma_2 x_1 + F_2 D^p(x_{1\tau} - x_{2\tau}) \end{array} \right.;$$

tion suppression system is less than or equal to the vibration displacement threshold; wherein the parameters of the vibration damping device comprises an initial damping force and damping force adjustable multiplying powers of the MR damper of the vibration damping device, a damping force and an inherent time delay of the passive damper of the damping device.

2. The vibration suppression method of the rolling mill roller assembly based on the vibration damping device according to claim 1, wherein the corresponding relationship of the freedom system with two degrees comprises:

$$\left\{ \begin{array}{l} m_1 \ddot{x}_1 + c_1 \dot{x}_1 + c_2 (\dot{x}_1 - \dot{x}_2) + k_1 x_1 + k'_1 x_1^3 + k_2 (x_1 - x_2) + P \cdot D^p(x_{1\tau} - x_{2\tau}) - F \cos(\omega t) = 0; \\ m_2 \ddot{x}_2 - c_2 (\dot{x}_1 - \dot{x}_2) + c_3 x_2 - k_2 (x_1 - x_2) + k_3 x_2 - P \cdot D^p(x_{1\tau} - x_{2\tau}) = 0 \end{array} \right.;$$

55

wherein, m_1 is the equivalent mass of the lower rolling mill roller assembly, m_2 is the equivalent mass of the mass block of the passive damper, and c_1 is the equivalent damping between the lower rolling mill roller assembly and the rolling piece, and k_1 is the equivalent linear stiffness, and k'_1 is the equivalent nonlinear stiffness, and c_2 is the equivalent damping of the lower rolling mill roller assembly and the passive damper, and k_2 is the equivalent stiffness of the lower rolling mill roller assembly and the passive damper, $F \cos(\omega t)$ is a periodic external excitation that the rolling mill is subjected; $P \cdot D^p(x_{1\tau} - x_{2\tau})$ is an equivalent damping

force of the MR damper of vibration the damping device between the lower rolling mill roller assembly and the passive damper; c_3 is an equivalent damping between the passive damper and a rolling mill stand of the lower rolling mill roller assembly, and k_3 is the equivalent stiffness of the passive damper and the rolling mill stand of the lower rolling mill roller assembly.

3. The vibration suppression method of the rolling mill roller assembly based on the vibration damping device according to claim 2, wherein S13 comprises the following steps:

S131: simplifying the corresponding relationship of the freedom system with two degrees to obtain a simplified corresponding relationship of the freedom system with two degrees;

S132: based on the initial damping force and the damping force adjustable multiplying powers, determining simplified equivalent damping force expressions of the MR damper;

S133: based on the simplified equivalent damping force expressions of the MR damper and corresponding relationship of a current freedom system with two degrees, performing the data processing to the freedom system with two degrees by a multiscale method, to obtain the first amplitude-frequency relationship.

4. The vibration suppression method of the rolling mill roller assembly based on the vibration damping device according to claim 3, wherein the corresponding relationship of the simplified freedom system with two degrees comprises:

$$\omega_{10} = \sqrt{\frac{k_1 + k_2}{m_1}}, \omega_{20} = \sqrt{\frac{2k_2}{m_2}}, \alpha_1 = \frac{c_1}{m_1}, \beta_1 = \frac{c_2}{m_1}, \beta_2 = \frac{c_2}{m_2},$$

$$\gamma_1 = \frac{k_2}{m_1}, \gamma_2 = \frac{k_2}{m_2}, \mu_1 = \frac{k'_1}{m_1}, F_1 = \frac{P}{m_1}, F_2 = \frac{P}{m_2}, F_0 = \frac{F}{m_1};$$

the simplified equivalent damping force expressions of the MR damper comprises:

$$\left\{ \begin{array}{l} F_1 \cdot D^p(x_{2\tau}) = \eta_1 \rho_1 D^p(x_{1\tau} - x_{2\tau}); \\ F_2 \cdot D^p(x_{2\tau}) = \eta_2 \rho_2 D^p(x_{1\tau} - x_{2\tau}); \end{array} \right.$$

wherein, η_1 and η_2 are initial damping force coefficients of the MR damper, ρ_1 and ρ_2 are damping force adjustable multiplying powers of the MR damper; the two second amplitude-frequency relationship comprises:

$$\begin{aligned} & \left(\frac{\eta_1 \rho_1 \omega_{10}^p a \cos\left(\frac{p\pi}{2}\right) e^{-i\omega_{10}\tau}}{2} - \omega_{10} a \sigma + \frac{3\mu_1 a^3}{8} \right)^2 + \\ & \left(\frac{\eta_1 \rho_1 \omega_{10}^p a \sin\left(\frac{p\pi}{2}\right) e^{-i\omega_{10}\tau}}{2} + \frac{\alpha_1 \omega_{10} a}{2} + \frac{\beta_1 \omega_{10} a}{2} \right)^2 = \frac{F_0^2}{4}. \end{aligned} \quad 5$$

5. A vibration suppression system of a rolling mill roller assembly based on a vibration damping device, wherein, the vibration suppression system comprising:

a controlling equipment, the vibration damping device being connected to the controlling equipment, and a rolling mill roller assembly being connected to the vibration damping device;

wherein the controlling equipment is configured to obtain first amplitude-frequency relationship during a vibration process of the rolling mill roller assembly vibration suppression system; and

the controlling equipment is configured to determine two time domain relationships and two second amplitude-frequency relationships by a simulation analysis, based on the first amplitude-frequency relationship; and

the controlling equipment is configured to adjust parameters of the vibration damping device until a vibration displacement of the rolling mill roller assembly vibration suppression system is less than or equal to a

vibration displacement threshold, based on the two time domain relationships and two second amplitude-frequency relationships;

wherein the vibration damping device comprises a mounting bearing, a magnetorheological (MR) damper, a passive damper, a supporting rod and a magnetic sucker;

wherein the rolling mill roller assembly comprises a rolling mill stand and a rolling mill roller, wherein the rolling mill stand is connected with the magnetic sucker, the rolling mill roller is connected with the supporting rod; and

wherein the controlling equipment is connected with the MR damper and the rolling mill roller; and

wherein the controlling equipment comprises a plurality of acceleration sensors, a first calculation member, and a second calculation member, and a controller; wherein two of the acceleration sensors are connected with each other, and the controller is connected with the MR damper;

wherein the MR damper is configured to determine the vibration displacement of the rolling mill roller through the acceleration sensors; and

wherein the MR damper and the passive damper is configured to absorb part of the vibration energy of the rolling mill roller.

* * * * *
